(No Model.)

J. A. MATTSON.
CARRIAGE STEP.

No. 499,327.

Patented June 13, 1893.

Fig.-1.

This technical drawing illustrates a device assembly, labeled 'Fig. 2.' at the top left. The assembly consists of several components: a vertical support structure with a central vertical axis; a top section featuring a vertical slot with a hatched pattern; a central vertical tube; and a base section. The base section includes a horizontal plate labeled 'RF' and a vertical support labeled '14'. Various parts are numbered with reference numerals such as 10, 11, 12, 13, 14, 15, 16, 17, 24, 26, 27, 28, 29, 30, 31, 32, 34, 36, 37, 38, 39, 40, 41, 42, 43, 44, 45, 46, 47, 48, and 49. The drawing uses lines and arrows to indicate the spatial relationships and assembly details of these parts.

UNITED STATES PATENT OFFICE.

JOHN A. MATTSON, OF DASSEL, MINNESOTA.

CARRIAGE-STEP.

SPECIFICATION forming part of Letters Patent No. 499,827, dated June 13, 1893.

Application filed January 7, 1893. Serial No. 457,555. (No model.)

To all whom it may concern:

Be it known that I, JOHN A. MATTSON, a citizen of the United States, residing at Dassel, in the county of Meeker and State of Minnesota, have invented certain new and useful Improvements in Carriage-Steps; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in steps for carriages, hacks, &c., and has for its objects to provide a durable, cheap, extensible carriage step that may be lowered down so as to form several steps, and raised so as to clear 20 safely over obstructions that might break the steps when the carriage is in motion. I attain these objects by the novel construction and arrangement of parts illustrated in the accompanying drawings, in which—

25 Figure 1, is a front elevation of my carriage step in its raised position. Fig. 2, is an edge view of Fig. 1, with a small portion of the carriage shown in section. Fig. 3, is a rear view of the step in the extended position shown in 30 dotted lines in Fig. 2. Fig. 4, is an enlarged sectional view on the line *a, a*, of Fig. 1. Fig. 5, is a perspective detail view.

Referring to the different parts of the drawings by reference numbers, 1, represents the 35 threshold; 2, the bottom of the carriage.

3, is an angularly formed plate secured by the bolts 4, and screws 7, to the carriage. To the plate 3, is secured by rivets 8, the plate 9, the front end of which forms the upper and 40 first step 10.

11, is the second step.

12, is the third and 13, is the fourth step.

The step 11, is formed of a single plate of metal having a forward bent portion 14, forming the step proper; a pendent body 15, provided at its top end with rearwardly extending flanges or lips 16, secured to the plate 9, by rivets as 8, or by bolts as 17, or where the article is cast from malleable iron or other cast 50 metal the parts 14, 15, and 9, and even the plate 3, may be cast in one piece.

18, are orifices cut out in the pendent bodies

of all the steps to reduce the quantity of materials and still retain such considerable width as will secure rigidity to the steps when lowered and hanging on pivots, as will presently be more fully described.

In the lower rear portion of the body plate 15, I secure rigidly the rivets 19, which project through the slots 20, in the body plate 21. 55 At the sides of said slots are provided recesses 22, for receiving the heads 23, of the pivots 19, making the heads 23, to come flush with the rear side of the plate 21, so that the next body plate 24, may slide over them. The pivots 19, 60 and their heads 23, serve to keep the plates 21, and 15, together, and permit the plate 21, to slide up and down on the plate 15. In the rear of the lower end of the plate 21, I secure rigidly the pivots 25, which extend through 65 the slots 26, in the plate 24, and are provided with heads 27, overhanging the rear side of the plates 24, so as to keep it together with the plate 21, and permit it to slide up and down on the latter.

70 The plate 9, is provided with downwardly extending lugs 29, (best shown in Fig. 5,) in said lugs I journal a small shaft 30, on which I secure between the lugs 29, a roller 31, to the face of which I secure by the screws 32, 75 the end 33, of the leather strap 34, which has its lower end 35, secured by rivets 36, to the bottom end of the plate 24. I further secure upon the shaft 30, a smaller roller 37, to the cylindrical face of which I secure by rivets 38, 80 the end of another strap 39, which extends upward through an aperture 40, to the inside 85 of the carriage where it is provided at its upper end 41, with a hand-hold 42.

44, is a peg secured in the plate 3, and projecting with its upwardly bent free end 45, through the woodwork of the carriage and engages in a hole 46, in the strap 39, for holding 90 the steps in the raised position.

When it is desired to lower the steps the 95 handle 42, is taken hold of, the strap 39, disengaged from the peg end 45, and the weight of the steps will cause them to slide down until the upper ones of the pivots 23, and 27, touch the upper termination of the slots 20, 100 and 26; while thus being lowered the steps will unwind the strap 34, from the roller 31, thereby winding the strap 39, onto the small roller 37. To raise the steps the handhold 42,

is raised which will unwind the strap 39, and wind the longer strap 34, upon the roller 31. 47, are guiding lugs formed upon the rear sides of the upper ends of the plates 21, and 5 24, for the purpose of keeping the said plates and the strap 34, centrally in line with each other, thereby securing proper and easy movement of said parts.

When it is desired to make these steps from 10 sheet metal (which may be preferable) the plate 9, may be stamped in two halves as indicated by the division line 48, in Fig. 5; this will allow the over-bent lugs 29, to be stamped any desired size.

15 I do not wish to confine myself to any exact difference between the size of the rollers 31, and 37, neither to the location of the peg 44, as it may in some cases be preferable to have the handle and peg within reach of the 20 driver upon the top of the carriage. It is also evident that chains or wire ropes may be substituted for the leather straps 34, and 39, and the number of steps may be increased or decreased without diverging from the spirit of 25 this invention.

What I claim as new, and wish to secure by Letters Patent, is—

1. The combination in a carriage step of the rigid plate 10, the pendent rigid plate 15, the 30 pivots 19, having heads as 23, the sliding plate 21, having the slots 20, and recesses 22, for the headed pivots to slide in, the pendent plate 24, the slots 26, headed pivots 27, steps 11, 12, and 13, the guiding lugs 47, and means 35 for raising and lowering said steps, substan-

tially as shown and described and for the purpose set forth.

2. The combination of the steps 11, 12, 13, the sliding extensible slotted plates 26, 21, the rigid plate 15, the plate 9, the lugs 29, the 40 shaft 30, journaled therein; the large roller 31, having a strap as 34, secured to it and to the steps to be raised, the smaller roller 37, strap 39, and handle 42, for by a short motion of the hand to cause a longer motion of the 45 steps in raising or lowering them and means for securing the strap 39, and the steps in either position and means for securing the steps to the carriage, substantially as shown and described.

3. In an extensible carriage step, the combination of a broad rigid plate as 15, the broad sliding plates 21, and 24, having slots as 20, and 26, near the outer edges for sliding and hanging on pivots or headed pegs, secured in 55 the next plate, said plates having a cutaway as 18, in the middle and horizontal portions as 11, 12, and 13, to step on, and are of such width between the slots and pegs by which they are joined together, that when the steps 60 are suspended the joints have no tendency to bend sidewise when a person steps on them, substantially as shown and described.

In testimony whereof I affix my signature in presence of two witnesses.

JOHN A. MATTSON.
